UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed November 3, 1922. Serial No. 598,897.

This invention relates to telephone systems, and more particularly to telephone systems employing automatic switches in completing some portion of a telephone connection.

One of the main features of the present invention, is the arrangement by which the talking connection extends only through non-numerical switches of the non-progressively movable type.

Another feature of this invention resides in the novel arrangement for counting impulses.

Other features will appear from the detailed description and appended claims.

In the drawings Fig. 1 represents two subscribers' lines with the substations associated therewith, which lines terminate in the connection terminals or springs of a primary cross bar switch. One spring combination of a portion of this cross-bar switch appears at the left of the dotted line of Fig. 1. Above and to the right of the dotted line of this figure there is represented a portion of a terminating secondary cross-bar switch, while below and to the right of the dotted line there appears a so-called originating secondary cross-bar switch. Fig. 2 diagrammatically shows a portion of a so-called bridge circuit, with which there is associated the testing, ringing, and battery feed arrangements of a talking connection. At the bottom of Fig. 2 there appears a portion of a so-called register cross-bar switch which serves to connect a register sender to a selected bridge circuit. Fig. 3 represents a register sender which includes a tens register and a units register of the relay type, as well as the circuits for controlling the same. At the upper right hand corner of this figure and partially bounded by the dotted lines there are represented five-multi-contact relays which are common to the lines of this system and which cooperate in the testing of these lines. Fig. 4 indicates the grouping arrangement of the line relays of the system, some of which are shown in the column at the left hand side of Fig. 4. At the right of this figure there appears the so-called vertical magnets, while at the bottom of this figure there are shown the horizontal magnets which actuate the horizontal bars 24 and the vertical bars 14 of Fig. 6. In the center of Fig. 4 there is disclosed a

step-by-step allotter switch which functions to assign an idle link circuit for use. Fig. 5 indicates the arrangement of the various relays by which the vertical magnets of a terminating cross-bar switch, which magnets are shown in a column at the right of this figure, and by which the horizontal magnets, shown in a row at the bottom of this figure, are controlled to complete a telephone connection. The circuits of the relays of Fig. 5 have not been shown connected into the remainder of the system but by reference to Figures 1 and 2 it will be readily understood that one of the rows of relays such as relay 136 is associated with each bridge circuit, while one of the relays of another row such as 150 is associated with an odd link circuit, and one of the relays of another row such as is designated 122, is associated with an even link circuit from which it should be understood that a relay such as 136 associated with the selected bridge circuit cooperates with a relay in one of the odd and even columns. The relays such as 150 and 122 are operated depending on whether the wanted line is odd or even to actuate the vertical magnet or horizontal magnet, by which the terminating cross-bar switch functions to build up a portion of the connection.

Figures 6, 7, 8, and 9 represent one form of cross-bar switch which may be used in the system of the present invention. Fig. 6 represents a side view of a portion of the cross-bar with many of its portions broken away for simplicity in disclosure. Fig. 7 represents two views of a so-called vertical cross-bar. Fig. 8 represents the detailed views of a set of interconnecting springs of the cross-bar switch, while Fig. 9 discloses a portion of a horizontal bar and a portion of the vertical bar to indicate how these bars cooperate to actuate the spring combinations of Fig. 8.

Fig. 10 is a representation of a relay such as may be used in a register sender of Fig. 3. The design of the windings of the relay 91 of this figure is such that both of the windings, one of which is high and the other low resistance, are energized in series. The spring 94 which may be considered as the armature spring engages the angular spring without changing the condition of the other contact sets. When, however, the relay 91 is energized by its low resistance winding,

the armature is fully attracted, so that the condition of all the contact sets is contrary to that shown in the figure.

The system.

While the present system may be of various sizes, for purposes of this description it will be assumed that it is arranged to provide service for a maximum of 90 lines, 10 these lines are arbitrarily divided into groups of 30 lines, which are still further sub-divided into sub-groups containing a so-called odd line and an even line, and when taken together are referred to as a pair.

15 These lines through the cooperation of the mentioned primary cross-bar switch have access to twenty-eight link circuits which are arranged into fourteen pairs. When one or more of a pair of telephone lines initiates a call, this pair of lines is extended through the primary cross-bar switch to an allotted pair of idle link circuits which have been assigned for use by the allotter switch of Fig. 4. Each of these link circuits is then 25 independently extended through an originating secondary cross-bar switch to any allotted one of ten bridge circuits and these ten bridge circuits are connectable through the operation of a register cross-bar switch 30 to any allotted one of five register senders.

By reference to Figs. 1 and 4 it will be seen that forty-five relays such as 51 are provided for 90 telephone lines. Only 35 twenty-three of these line relays have been shown, but the numbers appearing in the column at the extreme left of Fig. 4 indicate how the armatures and contacts of the remaining relays are connected into the system. While only twenty-one of the vertical 40 magnets of the primary cross-bar switch are shown, it will be understood that in a complete system there are forty-two of such magnets which are connected to the terminals of the allotter in the manner indicated by the numbers adjacent each of the 45 terminals which refer to the remaining vertical magnets. All of the horizontal magnets of the primary cross-bar switch are shown. In explaining why there are forty- 50 two vertical magnets and only fifteen horizontal magnets it should be stated, that since there are three groups of telephone lines, each of the horizontal magnets is common to a line in each of the three groups. This 55 is indicated by showing that the number 1 horizontal magnet is connected to the armature of the #1 line relay designated 51 and to the armatures of line relays #16 and #31. Also each link circuit appears before each of the three groups of telephone 60 lines, and since fourteen link circuits are provided, it is necessary to provide forty-two vertical bars, which is the product of fourteen times three.

65 In the secondary cross-bar switch, the

number of horizontal magnets is fourteen because there are fourteen link circuits, while the number of vertical magnets of the secondary originating cross-bar switch is twenty, since the fourteen link circuits are 70 connectable to ten bridge circuits. The showing of the vertical magnets, horizontal magnets, secondary line relays and the secondary allotter has not been made, but it will be understood that except for the number of the various relays and magnets it is similar to the grouping of these elements, as shown in Fig. 4. It will be understood that the number of secondary line relays is twenty-eight, and each of the fourteen horizontal magnets is connected to the armatures of two secondary line relays.

75 In this instance the secondary allotter is provided with only three brushes instead of four as in the case of the primary allotter, 80 and the number of terminals in the allotter bank is ten instead of fourteen as in the case of the primary allotter.

In the controlling circuits of the register cross-bar switch there are ten relays such 85 as that designated 81 in Fig. 2, one of these relays being associated with each bridge circuit. In this cross-bar switch there are five horizontal magnets and ten vertical magnets. The allotter associated therewith, 90 while it is controlled in a manner similar to the allotter of Fig. 4 is provided with only three sets of brushes, which engage five sets 95 or terminals.

In Fig. 5 there are shown the vertical and 100 horizontal magnets of a terminating cross-bar switch. In this instance there is no need for an allotter switch, since it is necessary to connect a bridge circuit selected by the calling line to the particular link circuit that has been seized by the called line. It will be seen that there are twenty vertical magnets such as 152 and fourteen horizontal magnets such as 153. The seizure of a 105 bridge circuit such as that at Fig. 2 effects the energization of the relay such as 136 and the testing and extension of the called line to a link circuit effects the energization of a relay such as 122. The operation of relays 136 and 122 causes the operation of vertical 110 magnet 152. The energization of relay 122 causes the operation of horizontal magnet 153. By referring to Figs. 1 and 2 it will be understood how the relays 122, 136, and 150 of Fig. 5 are connected in the various 115 links and bridge circuits of the system.

The switch structure.

A cross-bar switch which may be used in this system is structurally shown in Figs. 125 6 to 9 inclusive as having a frame member 10 with many supporting brackets on which various portions of the switch structure are mounted. The subscribers' lines and the trunks terminate in sets of resilient springs 130

generally designated 11, secured to the frame and shown in detail in Fig. 8. These sets of springs are very similar to the well known listening keys now in use except that 5 they are arranged to be operated automatically instead of manually. A bar 12 is arranged for horizontal motion either towards the right or towards the left and actuates the motor springs of the various sets while 10 a roller 13 mounted thereon is engaged by an irregular shaped spring or latch 14' to hold the bar and its actuated springs in the position to which it has been moved. It should be noted at this time that the bar 12 15 in either its right or left movement simultaneously actuates two sets of terminal springs as shown in the right hand view of Fig. 8. The mechanism for operating the various bars 12 includes a plurality of vertical bars 14 provided with a crank arm 15 and spaced extensions or lugs 16, all mounted for rotation in the frame 10. The rotation of the bar 14 is effected by expansive air chambers 17 and 18 commonly known 20 as "sylphons", operated by a supply of compressed air applied through an air supply pipe 19. The magnet 20 operates a valve 21 to release a supply of air into air chamber 17 while a magnet 22 actuates valve 23 25 to allow air to pass into the expansive air chamber 18. It will of course be understood that the number of vertical bars such as 14 will depend upon the number of lines which terminate in each switch. A plurality of horizontal bars 24 are likewise mounted for rotation in the frame 10. Each bar 24 has offset portions to prevent its interfering with the operation of the sets of terminal springs 11 and is also provided with 30 lugs 25 shown in detail in Fig. 9 and a crank portion not shown. The expansive air chamber 26 is mounted to engage the crank portion for rotating the horizontal bar 24 so that its lugs 25 are moved downward between the extensions 16 and 33 as 35 shown in Fig. 9. A magnet 27 actuates a valve 28 to release air into the expansive chamber 26 to rotate bar 24. A second series of vertical bars 29 are provided with 40 triangular openings such as 30, which function to restore bars 12 to normal position. Each opening in bar 29 receives a roller such as 31 carried on the end of bar 12 so that when the release bar 29 is elevated the 45 roller 31 engages the sides of the opening 30 to move the bar 12 with its motor springs into neutral position as shown in Fig. 6. A set of three release bars 29 is actuated by 50 the expansive air chamber 32 but this is due to the coupling of lines and trunks in the cross-bar switch.

In the operation of the primary switch a pair of idle link circuits is normally allotted for use as will be described so that on 55 the initiation of a call, a magnet such as

27 operates a valve 28 which in turn admits air into expansive air chamber 26 to rotate the horizontal bar 24. This operation brings the lugs 25 between sets of lugs 16 and pairs of arms 33 carried by the bars 12, 70 then either magnet 20 or 22 is operated. Let it be assumed that the magnet 20 is operated to actuate its valve 21 to release air into the expansive air chamber 17, which rotates the vertical bar 14 towards the left. 75 The lug 25 communicates this motion through extensions 33 to move the bar 12 towards the left until the roller 13 engages the left hand catch of spring 14'. This catch tends to hold the line and link terminals in engagement until the time that a release magnet such as 34 operates a valve 35 to actuate the expansive air chamber 32. This elevates the set of three release bars 29 to move the bar 12 and its motor springs 80 to normal position. 85

The structure of the primary and secondary cross-bar switches is the same except that in the primary cross-bar switch the number of spring combinations 11 as well 90 as the number of release bars is greater than those of the secondary cross-bar switch. It will be seen from Fig. 6, that in the primary cross-bar switch the spring combinations, such as 11 comprise four sets 95 of line and trunk terminals and the release bars are arranged in groups of three, each group being actuated by the operation of a single expansive chamber, such as 32.

In the secondary cross-bar switches, the 100 spring combinations such as 11 include the two sets of springs corresponding to what is known as an odd spring combination or an even spring combination. Also in the secondary cross-bar switches the release bars 105 are arranged in groups of two, each group being operated by a single expansive chamber.

The register cross-bar is similar in structure and operation to the primary and 110 secondary cross-bar switches.

Operation of the system.

It is believed that the invention will best be understood by describing the method of establishing a telephone connection from a 115 substation such as A to a substation herein designated B, and to which the designation #10 is assigned.

When the subscriber at A removes his receiver from its switch hook a circuit is closed from grounded battery, armature and back contact of relay 50, back contact and continuity spring of relay 51, right hand winding of this relay, contact 53 and armature 120 of cut-off relay 52, over the lower side of the calling line, through the substation circuits in series, over the upper side of the calling line, armature and contact 54 of relay 52 to ground. The relay 51, operates and closes 125 130

its contacts 55 and 56 to operate the predetermined vertical magnet and the predetermined horizontal magnet of the cross-bar switch so that the two sets of cross-bar switch springs, generally designated 57, are closed. The operation of the cross-bars of the switch is effected by the closure of the following circuits: On the operation of the relay 51, a horizontal bar magnet such as the first of the series in Fig. 4, is energized from grounded battery, winding of this magnet, armature and contact 56 of relay 51 and thence to ground. The vertical bar magnet such as the first of the series in Fig. 4 is operated from grounded battery, front contact and armature of the operated horizontal magnet, armature and back contact of the relay 192, brush 194 in its first position through the vertical magnet to the contact 55 and armature of relay 51 and thence to ground. The operation of the horizontal and a vertical magnet operates the vertical bar and a horizontal bar of the cross-bar switch to close two sets of contacts in the manner already described. As soon as the set of contact springs 58 is closed the operating circuit of cut-off relay 52 is completed causing it to attract its armatures and thereby disconnect a pair of lines such as #10 and #19 from the line relay 51. At this time the calling line is extended through contacts 59 and 60 to that portion of the secondary cross-bar switch that is assigned to odd originating telephone lines. Also the closure of the set of springs 57 extends the telephone line from substation B through springs 61 and 62 to that portion of the secondary cross-bar switch that is assigned to even originating telephone lines.

It should be mentioned at this point that the calling line #19 and the called line #10 are extended by the closure of the single set of springs 57 merely because these two lines happen to be paired together. Also if one of a pair of lines originates a call both of these lines are simultaneously extended to a pair of idle trunks. When the calling line is extended through contacts 59 and 60 a circuit is completed for the relay 63 from grounded battery, winding of this relay, contact 64 and armature of secondary cut-off relay 65, conductor 66, through contact springs 60 and the calling line in series, contact springs 59, conductor 67, contact 68 and armature of relay 65 to ground. The relay 63 on operating closes its contacts 69 and 70 which complete operating circuits for the vertical and horizontal magnets associated with the contacts 71, 72, and 73. These magnets operate and close these contacts to further extend the calling lines over conductors 66 and 67 to the conductors 74 and 75 of the secondary trunk leading to the originating end of a so-called bridge circuit.

The closure of contacts 73 completes an ener-

gizing circuit for relays 140 and 65. Relay 65 at its middle armature and front contact applies a ground potential to the test contact of the allotter of Fig. 4 which is individual to the pair of links of Fig. 1. At this time the relay 192 is energized from grounded battery, relay 192, test brush 191, and the mentioned grounded test contact. With relay 192 energized, an operating circuit is closed for motor magnet 193 which causes it to advance the allotter brushes 191, 194, 195, and 196 until test brush 191 locates an idle pair of link circuits.

The extension of a calling line to conductors 74 and 75 completes a circuit through the left hand winding of relay 76 to ground, and through contact springs 77, conductor 78 and right hand winding of relay 76 to grounded battery. Relay 76 energizes and completes a circuit from ground, conductor 79, armature and back contact of relay 80, winding of relay 81 to grounded battery. Relay 81 closes its contacts 82 and 83 whereby the vertical and horizontal magnets of a so-called register cross-bar switch operate to connect an allotted register sender to the bridge circuit. Simultaneously with the energization of relay 81, slow releasing relay 84 is actuated from grounded battery, over conductor 79 to ground at the front contact and armature of relay 76 and when the springs 85 of the register cross bar switch are closed, relay 80 is operated from grounded battery, its winding, inner front contact and armature of relay 84, contact springs 85 to ground. On the closure of contacts 86 of the register cross-bar switch an impulse circuit is extended from grounded battery, winding of the impulse relay 87 of Fig. 3, conductor 88, contact springs 86, over conductor 75 to the lower side of the calling line and through the substation circuits, over the upper side of the calling line, conductor 74, left hand winding of relay 76 to ground. The impulse relay is thus energized and effects the operation of the slow releasing relay 88 from grounded battery, resistance, winding of this relay, continuity spring and armature of relay 87 to ground. The operation of relay 88 in turn effects the actuation of the slow releasing relay 89 which relay at its uppermost armature and front contact applies a busy condition to the contacts assigned to this register sender at the sender allotter. The relay 88 also effects the energization of slow releasing relay 112. The circuits are now in condition to receive directive impulses corresponding to the designation of a called line which in the case assumed is #10.

The subscriber at A thereupon operates his dial sender to transmit one impulse which effects the momentary release of the impulse relay 87. This operates change-over relay 90 in a circuit from grounded battery, wind-

ing of relay 90, inner front contact and armature of relay 88, back contact and continuity spring of relay 87 to ground. Also a multiple operating circuit is closed for the counting relay 91 of the tens relay register. This circuit is traceable from grounded battery, through the low and high resistance windings of relay 91, back contact 92 and armature of this relay, back contact and armature of 10 switching relay 93 to ground at the back contact and continuity spring of relay 87 as previously described. The relay 91 is so designed that it attracts only its armature 94 when both of its windings are included in series, 15 with the result that when impulse relay 87 is again operated a circuit is closed from ground, continuity spring and armature of the impulse relay, conductor 95, left hand back contact, continuity spring and armature 20 of relay 91, left hand winding of this relay to grounded battery. At this time relay 91 attracts both of its armatures and thereby extends the impulse circuit to the #2 counting relay of the tens register.

25 During the time that the change-over relay 90 is operated, while the tens series of impulses is being transmitted, a circuit is closed from grounded battery, through the high and low resistance windings of relay 93, its outer back contact and armature, continuity spring and armature of relay 90 to ground. The relay 93 is similar in structure to the relay shown in Fig. 10 so that the circuit just described is effective only to 30 bring the inner armature 94 of this relay into engagement with its continuity spring without opening any of the back contacts. At the close of the tens series of impulses, however, the change-over relay deenergizes and 35 thereby completes a circuit from ground, its continuity spring and back contact, back contact, continuity spring and armature of relay 93, its low resistance winding to grounded battery. The relay 93 is completely energized in this last circuit and attracts its armatures and through its inner armature, continuity spring and front contact closes a locking circuit for itself through its left hand winding and the holding conductor 40 97 to ground through the left hand front contact and armature of relay 88. The operation of relay 93 also removes the tens register relays from the control of the impulse relay 87 and directly connects the control 45 of this last relay to the group of relays of the units register. The register sender is now in condition to receive the units impulse of the wanted number which in the case assumed was "0". The calling subscriber 50 thereupon proceeds to send ten impulses corresponding to "0" and in response to each of these impulses, impulse relay 87 retracts and attracts its armature. In response to the first of these impulses the change-over 55 relay 90 is again energized from grounded

battery its winding, through the inner front contact and armature of relay 88, continuity spring and armature of relay 87 to ground. A circuit in multiple of that just described is also completed from ground, continuity 60 spring and back contact of relay 87, inner armature and front contact of relay 88, left hand armature and front contact of relay 93, back contact and armature 99 of relay 98, through both windings in series of this relay 65 to grounded battery. Relay 98 is only partially operated in this circuit to bring its armature 100 into engagement with its continuity spring without interrupting its back contact. When, however, the impulse relay 70 again attracts its armature it completes a circuit from ground its continuity spring and armature, outer back contact, continuity 75 spring and armature 100, left hand winding of relay 98 to grounded battery in which circuit relay 98 fully attracts its armatures. At its armature 99 and front contact relay 88 extends the impulse repeating circuit to the #2 counting relay 101. On each retraction and attraction of the armature of the 80 relay 87 one of the units register relays is operated and since it was assumed that the called subscriber sends ten series of impulses corresponding to the units digit, all of these 85 ten relays are operated.

At the time when the change-over relay attracted its armature in response to the first units impulse, a circuit for the switching relay 102 was closed from ground at the 90 continuity spring and armature of relay 90, outermost armature and front contact of relay 93, through both windings in series of relay 102 to grounded battery. The relay 102 is partially operated in this circuit to bring its armature 103 into engagement with 95 its continuity spring. At the close of the units series of impulses when the changeover relay 90 is again deenergized, the relay 102 is fully operated in a circuit now closed from 100 grounded battery, through its low resistance winding, armature 103, its continuity spring and back contact, back contact and continuity 105 spring of relay 90 to ground.

At the close of this last series of impulses, if no other one of the register senders is testing for a called line, the relay 104 effects the test of the wanted line #10. There is a relay similar to 104 at each of the five register senders of the system and the circuits through the contacts of these relays are so arranged that if any one of the relays is operated no other relay corresponding thereto can be simultaneously actuated. This is shown in applicant's copending application Serial #583,113, filed August 21, 110 1922 issued as Patent No. 1,531,219, Mar. 24, 1925. Since it was assumed that no other register sender is ready to test a called line at this time, a circuit is closed from ground 115 at the last switching relay similar to 104 in 120 130

series, through the back contact 105 and the continuity spring of relay 104, through both windings in series of this relay, right hand armature and front contact of relay 102, 5 through armatures 106, 107, 108 and 109 of the actuated units register relays, conductor 110 and winding of the #5, multi-contact test relay 111 to grounded battery. It will be understood that the group of common multi- 10 contact relays controls the test circuits of all of the telephone lines in the same manner as relay 111 controls the test circuit of the present called line.

Relays 104 and 111 are operated in this 15 circuit and relay 111 attracts its armatures to close break-points in the test circuits of this group of lines. The relay 104 interrupts the operating circuit of the slow releasing relay 112 and the first mentioned 20 relay at its right hand armature and front contact closes a test circuit from ground at the right hand armature and front contact of relay 88, right hand armature, front contact of relay 104, continuity spring and armature of relay 112, conductor 113, winding of slow releasing relay 114, armature 25 115 and back contact of relay 96, conductor 116, contacts 117 of multi-contact relay 111, conductor 118, and if the cut-off relay of the 30 pair of lines in which the called line is included is not operated, this circuit is extended through the left hand winding of a relay similar to 51, its continuity spring and back contact, back contact and armature of 35 a relay similar to 50 to grounded battery. The relay 51 operates in the manner already described to cause the primary cross-bar switch to extend the called line to an idle primary trunk. Since it has been assumed, 40 however, that the called line is paired with the calling line, the primary cross-bar switch is already operated and the called line is extended to an idle primary trunk so that the test circuit including conductor 118 instead 45 of being completed through the line relay 51 is extended through contacts 119 and conductor 120, outermost back contact and armature of relay 121, winding of relay 122, conductor 123, through the outermost left 50 hand continuity contacts and armatures of all the operated units register relays in series, conductor 124, left hand front contact and armature of relay 104, resistance, to grounded battery. Relay 122 is operated in 55 this circuit and since it is a secondary line relay associated with an even terminating position of the secondary cross-bar switch it causes the vertical and horizontal relays to operate the set of springs generally designated 125 to connect the called line to the terminating end of the bridge circuit of Fig. 2 to which it has been assumed the calling line has been connected.

When the relay 84 is operated, it closes

an acuating circuit for the ringing relay 126 65 from grounded battery resistance, winding of this relay, conductor 127, right hand front contact and armature of relay 84 to ground. When, therefore, the called line and substation B is extended through the primary and 70 secondary cross-bar switches to conductors 128 and 129 by the operation of the even cross-bar switch springs 125, ringing current is supplied from the generator through the winding of the trip relay 131, front contact 75 and right hand armature of relay 126, over conductor 129 to the substation at B and the signal thereon, over the upper side of the extended connection, over conductor 128, left hand front contact and armature of relay 80 126 to ground over conductor 127. The called party at substation B signalled in this manner and when he responds by removing his receiver from its switch hook, trip relay 131 receives sufficient current to operate 85 and attracts its armatures. At its left hand armature and front contact, it short circuits the ringing relay 126 causing this relay to deenergize, after which the trip relay 131 is locked operated in a circuit from 90 grounded battery, right hand winding of the trip relay, its front contact and armature, left hand back contact and armature of ringing relay 126 to ground at the front contact and right hand armature of relay 84. 95

It will be noted that battery feed relay 132 is operated as soon as the ringing relay deenergizes and closes its armature and back contact so that talking battery is supplied to the called party through the windings of 100 relay 132, while talking battery is supplied to the calling party through the windings of relay 76.

It should be noted that as soon as the test of the called line is made, the register sender 105 is released. This is brought out in the following manner. The circuit of relay 114, which it will be recalled is included in the test circuit of the wanted line, is interrupted by the release of relay 112, and when relay 110 114 deenergizes it short circuits and releases the holding relay 88 which has been holding the register sender during its operation. This short circuit is completed from grounded battery, resistance, front contact and armature of relay 89, uppermost back contact and armature of relay 114, lowermost back contact and armature of relay 112 to ground. When relay 88 is thus deenergized, it also 115 opens the circuit of slow releasing relay 89, 120 which has been maintaining a busy potential on the test terminal of the sender allotter. However, before relay 89 deenergizes a circuit is completed from ground, left hand armature and back contact of relay 88, inner 125 armature and front contact of relay 89 and winding of the release magnet 134 to grounded battery, which operates magnet

134 in a manner already described to restore the operated contact springs of the register cross-bar switch to normal position.

Let it now be assumed that the wanted line is busy at the time when the test thereof is made, as a result of which condition the test circuit including conductor 118 is open either at the armature and back contact of cut-off relay 52 or at the armature and back contact of relay 121 so that relay 114 is not operated. Instead of this, the test relay 135 is energized from grounded battery, its winding, continuity spring and back contact, armature and back contact of relay 136, contact springs 137, conductor 138, inner back contact and armature of relay 114, conductor 131, innermost back contact and armature of relay 112, front contacts and armatures of relays 104 and 88 to ground. The test relay 135 is energized in this circuit and at its continuity spring and armature closes a locking circuit for itself to ground at the right hand front contact and armature of relay 80, which circuit is held complete until the calling party releases. With relay 135 operated the busy tone current is transmitted to the calling station from the source BZ through the right hand armature and front contact of relay 135 and over the connection already established to the calling substation.

At the termination of the connection when the calling subscriber replaces his receiver on its switch hook, the battery feed relay 76 releases to effect the deenergization of relays 80 and 84. It will be understood, however, that in the interval between the release of relays 80 and 84, a circuit is completed through the release magnet 139 of the originating cross-bar switch of Fig. 1 causing this magnet to operate and restore the operated originating springs of the secondary cross-bar switch in the manner already described. The release of the originating cross-bar switch opens the contacts 73, which immediately causes the deenergization of relay 65 and shortly afterwards causes the deenergization of slow releasing relay 140. In the interval between the deenergization of these two relays a circuit is closed from ground, armature and front contact of relay 140, armature and back contact of relay 65, right hand armature and back contact of relay 121, winding of the release magnet 142 to grounded battery. The release magnet 142 is thus operated and restores the operated contacts of the primary cross-bar switch to their normal position.

When the called subscriber replaces his receiver on its switch hook, the battery feed relay 132 deenergizes causing the deenergization of the slow releasing relay 143, and the release of this last named relay shortly afterwards effects the deenergization of relay 144. In the interval between the release

of these two relays, a circuit is closed from ground, armature and back contact of relay 143, armature and front contact of relay 144, conductor 145, winding of the release magnet 146 of the terminating cross-bar switch 70 which effects the release of the operating contact springs thereof in the manner already described.

What is claimed is:—

1. In an automatic telephone system, a 75 plurality of telephone lines, a plurality of link circuits, a cross-bar switch, contacts of said telephone lines and contacts of said link circuits in said cross-bar switch, means operative on the initiation of a call on one 80 of said lines for closing a contact of said line and a contact of an idle link circuit, means directly controlled over the calling line for closing a contact of the called line and a contact of a second link circuit, 85 and means for interconnecting said selected link circuits.

2. In an automatic telephone system, a plurality of telephone lines arranged in pairs, a plurality of trunks, a cross-bar 90 switch having contacts by which said telephone lines and trunks may be automatically connected, means responsive to the initiation of a call on one of said telephone lines of a pair for connecting said pair of 95 telephone lines to a pair of idle trunks, means controlled over said calling telephone line for connecting the called telephone line to an idle trunk, and means for interconnecting the trunks to which the calling and 100 called telephone lines are connected.

3. In an automatic telephone system, a plurality of telephone lines, a plurality of link circuits, a plurality of bridge circuits, means including a primary cross-bar switch 105 for interconnecting a calling telephone line and an idle link circuit, a secondary cross-bar switch for interconnecting a selected link circuit and an idle bridge circuit, a plurality of register senders, means including another cross-bar switch for connecting the selected bridge circuit to an idle register sender, means controlled over the calling telephone line for directly operating the selected register sender to store the designation 110 of the called telephone line, means controlled by said register sender for causing said primary cross-bar switch to extend the called telephone line to another link circuit, an additional secondary cross bar switch, 115 means operative on the seizure of said second link circuit for operating said last mentioned cross-bar switch to connect said link circuit to the previously selected bridge circuit, and means responsive to said connection for releasing said register sender.

4. In an automatic telephone system, a plurality of telephone lines, a plurality of bridge circuits, a plurality of non-numerical switching means for extending said tele- 125

- phone lines to said bridge circuits to complete a telephonic connection, means responsive to the initiation of a call on one of said telephone lines for causing said non-numerical switching means to extend said telephone line to an idle bridge circuit, a plurality of register senders each including a plurality of groups of counting relays arranged to be variably operated to store the 10 designation of a called telephone line, and means controlled by the operation of one of said register senders for causing said non-numerical switching means to extend the called telephone line to the selected bridge circuit.
5. In an automatic telephone system, a plurality of telephone lines, a plurality of bridge circuits, a plurality of non-numerical switches for extending said telephone lines 20 to said bridge circuits to complete telephonic connections, means responsive to the initiation of a call on one of said telephone lines for causing said non-numerical switching means to extend said telephone line to an idle bridge circuit, a plurality of register senders each including a plurality of groups of counting relays arranged to be variably operated to store the designation of a called telephone line, means controlled by the operation of one of said register senders for causing said non-numerical switching means to extend the called telephone line to the selected bridge circuit, and means responsive to the interconnection of said calling and called telephone lines for releasing said operated register sender.
6. In an automatic telephone system, a plurality of telephone lines, a plurality of bridge circuits, non-numerical switching 40 means for interconnecting said telephone lines and said bridge circuits, means responsive to the initiation of a call on one of said telephone lines for operating said non-numerical switching means to extend the same to an idle bridge circuit, a plurality of register senders each including a plurality of groups of counting relays arranged to be variably operated to designate a called telephone line, the relays of each group being 45 operated in succession, a test circuit for each of said telephone lines by which the operation of said non-numerical switching means is initiated to extend the called telephone line to a selected bridge circuit, means including said groups of relays for completing the test circuit of the called telephone line, and means responsive to the interconnection of the calling telephone line and called telephone line for releasing the operated register sender.
7. In an automatic telephone system, a plurality of telephone lines, a plurality of bridge circuits, means including non-numerical switching means for extending said telephone lines to said bridge circuits, a plurality 55 of register senders each including groups of relays arranged to be variably operated in accordance with one or more digits of the designation of the called telephone line, means responsive to the initiation of a call on one of said telephone lines for causing said non-numerical switching means to extend the same to an idle bridge circuit, means responsive to said extension for associating an idle register sender with the selected bridge circuit, means controlled over said calling telephone line for variably operating said groups of relays, a test circuit for each telephone line, a group of multi-contact relays, means including the 60 groups of relays of the associated register sender and said multi-contact relays for completing the test circuit of the called telephone line, means responsive to the completion of said test circuit for causing said non-numerical switching means to extend the called telephone line to the selected bridge circuit, means for thereupon signaling the called telephone line, means effective on the response of the called subscriber for disabling said signaling means, and means for effecting the release of said register sender.
8. In a system of the class described, a series of relays arranged to be operated in succession, each relay being operated in two distinct stages and subsequently released, and means for operating said relays.
9. In a system of the class described, means for generating a series of impulses, and a series of relays controlled by said series of impulses, each relay being operated in two distinct stages in response to an impulse and being subsequently released.
10. In a system of the class described, two series of relays, the relays of each series being arranged to be operated in succession, each relay being operated in two distinct stages, common governing means for said series of relays, and means for transferring the control of said governing means from one series of relays to the other series.
11. In a system of the class described, two series of relays, the relays of each series being arranged to be operated in succession, each relay being operated in two distinct stages and subsequently released and common governing means including a switching relay operating in two distinct stages.
12. In a system of the class described, an impulse relay arranged to be energized and deenergized in response to directive impulses from a distant point, and a series of relays arranged to be operated in two distinct stages in succession, each relay being operated one stage in response to the deenergization of said impulse relay and prior to its release being operated another stage in response to the subsequent energization of said impulse relay.

13. In a system of the class described, means for generating a series of impulses, and a series of relays for counting said series of impulses, each relay being provided with two sets of contacts operated at different times, one of said sets of contacts being operated at the beginning of each impulse of the series and the other of said sets of contacts being operated at the close of each impulse of the series.

14. In a system of the class described, means for generating a series of impulses, and a series of relays for counting said series of impulses, each relay having a high resistance winding and a low resistance winding, the windings of each relay functioning to operate it in two distinct stages in response to each impulse.

15. In a system of the class described, means for generating a series of impulses, a series of relays controlled by said series of impulses, each relay being provided with two windings and two sets of contacts, means operating in response to an impulse for energizing both of said windings to close one of its sets of contacts, and other means controlled in response to said impulse for energizing one of said windings only to close both of said sets of contacts.

16. In an automatic telephone system, a plurality of telephone lines, a plurality of link circuits, a cross-bar switch, contacts of said telephone lines and contacts of said link circuits in said cross-bar switch, means operative on the initiation of a call on one of said lines for closing contacts of said line and contacts of an idle link circuit, a bridge circuit, means including non-numerical switching means for extending the selected link circuit to said bridge circuit, means directly controlled over the calling line for closing contacts of the called line and contacts of a second link circuit, and means for interconnecting said last mentioned link circuit and said bridge circuit.

17. In an automatic telephone system, a plurality of telephone lines arranged in pairs, a plurality of trunks, a cross-bar switch having contacts by which said telephone lines and trunks may be automatically interconnected, means responsive to the initiation of a call on one of said telephone lines of a pair for connecting said pair of telephone lines to a pair of idle trunks, a bridge circuit, non-numerical switching means for extending the trunk connected to the calling line to said bridge circuit, means controlled over the calling line for connecting the called telephone line to an idle trunk, and means for interconnecting said last mentioned trunk and said bridge circuit.

18. In an automatic telephone system, a plurality of telephone lines, a plurality of link circuits, non-numerical switching means including bars extending at substantially right angles to each other for extending telephone lines to idle link circuits, the number of said bars being greater than the number of said link circuits, a bridge circuit, non-numerical switching means for extending a selected link circuit to an idle bridge circuit, means controlled over the calling telephone line for causing said first mentioned switching means to extend the wanted telephone line through a second link circuit to said bridge circuit.

19. In an automatic telephone system, a plurality of telephone lines, a plurality of link circuits, a cross-bar switch, contacts of said telephone lines and contacts of said link circuits in said cross-bar switch, means operative on the initiation of a call on one of said telephone lines for causing contacts of said plurality of telephone lines to engage contacts of a plurality of said link circuits whereby each one of said plurality of link circuits is selected by a different one of said telephone lines, and means including only non-numerical switches and link circuits for extending the link circuit selected by the calling telephone line to a wanted telephone line.

20. In an automatic telephone system, a plurality of telephone lines arranged in pairs, a plurality of link circuits also arranged in pairs, a cross-bar switch, contacts for each pair of telephone lines and contacts for each pair of link circuits in said cross-bar switch, means operative on the initiation of a call on one of said telephone lines for closing a set of contacts of a pair of lines including said calling telephone line and the contacts of a pair of link circuits, and means including only non-numerical switches and trunk circuits for extending the link circuit connected to the calling telephone line to the wanted telephone line.

In witness whereof, I hereunto subscribe my name this 2nd day of November, A. D. 1922.

In witness whereof, I hereunto subscribe my name this 2nd day of November, A. D. 1922.

WINFRED T. POWELL
